UNITED STATES PATENT OFFICE

JOSEPH J. STOETZEL, OF BELLAIRE, NEW YORK, ASSIGNOR TO G. & G. ATLAS SYSTEMS, INC., OF NEW YORK, N. Y., A CORPORATION OF NEW YORK

PNEUMATIC DISPATCH TUBE SYSTEM

Application filed October 17, 1925. Serial No. 62,965.

This invention relates to pneumatic dispatch tube systems, and particularly to such systems of the type known as "open systems". By the term "open systems" I mean systems in which each line is provided with an open end or bell mouth, into which carriers may be inserted directly and without the preliminary opening of a gate or valve, or, in other words, systems in which each line is normally open to the atmosphere at one end.

In these systems each line generally communicates at the delivery end with an exhauster of some suitable type so that when a carrier is inserted in the line it will be drawn through it by suction. Of course, if the full suction is maintained on the system at all times, whether there is any carrier to be transmitted or not, there will result a great waste of power.

The general object of the present invention is to provide a simple and efficient controlling device for such systems, which will reduce this waste of power to a minimum.

The more specific objects of my invention will appear more fully hereinafter.

In the accompanying drawings Fig. 1 illustrates a typical "open" tube system to which my invention is applied; Fig. 2 is a sectional view of the preferred form of my controlling device, with the valve in its normal closed position; Fig. 3 is a fragmentary view of the valve of Fig. 2 showing the valve in its open or transit position; and Figs. 4, 5 and 6 are views partly in section of modified forms of the controlling device.

Referring first to Fig. 1, 10, 11, represent the transit tube. In department stores and similar places where these systems are used extensively, the open end or bell mouth 12 is usually situated at the central cashier's station A, as is the delivery end 13 which is provided with a door 14, normally held closed as shown, by spring means. Intermediate the two ends 12 and 13 is located the salesman's station B where the line is provided with a carrier exit 15, normally closed by the spring pressed door 16, and with a carrier entrance 17, normally closed by a spring pressed door 18. Suction for conveying carriers through the transit tube 10, 11,

is provided by an exhaust drum 19, or equivalent device, through the exhaust conduit 20 which communicates with the transit tube 11 adjacent the delivery end 13.

The lay-out above described is well known. In operation, when a salesman at B desires to have change made, for example, he places the money and the sales slip in the usual cylindrical carrier and, opening the door 18, inserts the carrier into the tube 11. The suction applied adjacent the delivery end draws the carrier to that end of the system, where it pushes open the door 14 and drops out of the tube. The cashier then makes the necessary change in the contents of the carrier and places it into the tube 10 through the open end or bell mouth 12. The doors 14, 16 and 18, being closed, the suction applied at the delivery end 13 is effective to draw the carrier through the tube 10, from which it emerges at the salesman's station B through the exit 15, pushing open the door 16 in a manner well understood.

It is evident that in a system of this character, unless some means are provided for preventing it, a large volume of air will constantly be sucked through the transit tubes, whether any carriers are being transmitted or not. This, of course, is very wasteful of power. Accordingly I have provided, in the exhaust conduit 20, a controlling device 21 which normally reduces the flow of air through the transit tubes to almost nothing, but which automatically applies full suction the moment a carrier is inserted into the transit tube. As soon as the carrier leaves the tube the suction is again cut down.

The construction and operation of this controlling device can best be understood from Figs. 2 and 3. This device includes a port 22 and a valve 23 for controlling that port. This valve, which may be of any suitable construction, such as those here shown, is connected by means of a valve stem 24 with a diaphragm 25. This diaphragm divides the casing in which it is mounted into two chambers, 26 at the left (as viewed in Fig. 2) and 27 at the right. The chamber 26 is open to the atmosphere, and the chamber 27 is normally maintained at the same pressure as the exhaust

conduit by the communicating passage 29. The normally closed valve 30 when opened admits the atmosphere to the chamber 27 through the pipe 30a. If desired the valve 30 may control a port in the passage 29, and the pipe 30a may then be omitted.

I shall now describe the way in which the valve 23 is opened automatically upon the insertion of a carrier into the tube.

With the valve in the closed position illustrated in Fig. 2, but a slight amount of air is drawn through the exhaust conduit 20 and transit tubes 10, 11, by the exhauster. This slight amount of air, or "minimum flow", traverses the by-pass consisting of the passage 29, chamber 27 and adjustable passage 29a. Since the transit tubes are normally open to the atmosphere at the end 12, the pressure within those tubes and within the exhaust conduit 20 is normally at substantially atmospheric pressure, the flow of air through the by-pass being insufficient to reduce the pressure materially. The spring 31 is of sufficient force to hold the valve 23 in the closed position shown in Fig. 2 so long as the conditions just described exist in the tube system. However, as soon as a carrier is inserted either into the open bell mouth 12 or into the entrance 17 of the transit tube, the portions of the tubes in advance of the carrier are cut off from communication with the atmosphere, as, of course, is the exhaust conduit 20. Immediately the small flow of air through the by-pass establishes a partial vacuum in the portion of the system which has been cut off from communication with the atmosphere. And since the chamber 27 at the right of the diaphragm 25 is in communication with that portion of the system, the pressure in that chamber is reduced, and as the result the atmospheric pressure in the chamber 26 pushes the diaphragm to the right and thus opens the valve 23. This, of course, establishes the full flow of air through the system and transmits the carrier through the tube, from which it is delivered through the door 14 or the door 16, as the case may be.

Upon the delivery of the carrier there is, of course, a rush of air through the port 22. This rush of air operates by its kinetic energy upon the vane 32 to which the valve 30 is connected and thus opens the valve 30 and admits the atmosphere to the chamber 27. The pressure in the chamber 27 is thus increased sufficiently so that the spring 31 is able to restore the valve 23 and the diaphragm 25 to their normal positions of Fig. 2.

The valve shown in Fig. 4 is similar in construction and operation to that of Figs. 2 and 3. The main differences are: (1) instead of providing a by-pass for the normal "minimum flow", this is provided for by holding the valve 23 slightly off its seat by means of an adjusting screw 40, and (2) the right hand

side of the chamber 27, instead of being rigid and provided with a cylindrical opening through which the stem 24 passes, is a flexible wall 27a connected to the valve stem 24. In this valve, also, the left hand side of the diaphragm 25 is protected by a casing cover 26a and communicates with the atmosphere through an opening such as 28. In the case of this valve, as in the case of the valve of Fig. 2, the insertion of a carrier into the system cuts off communication with the atmosphere through the bell mouth and thus reduces the pressure in the tube and, by reason of the presence of the communicating passage 29, in the chamber 27 also. As a result the atmospheric pressure on the other side of the diaphragm 25 pushes it and the valve stem and valve to the right, thus opening the valve. The passage 29 may be restricted by the adjusting screw 29b. The closure of the valve is by the action of the vane 32 as above described.

The construction of Fig. 5 also provides for the "minimum flow" by normally holding the valve 23 slightly unseated. This is one point of difference between this valve and that of Fig. 2. The other point of difference is that the communication between the chamber 27 and the exhaust conduit, instead of being ahead of the valve 23 through the passage 29, is beyond the valve 23 through a passage 41 surrounding the valve stem. In operation, the placing of a carrier into the system causes a drop of pressure in the conduit 20, including the chamber 42, and therefore in the chamber 27. Further description of the operation is believed to be unnecessary in view of the full description given with reference to the structure of Fig. 2. In some instances, with valves of this character it is necessary to provide a slow leak to the atmosphere from the chamber 27 in order to raise slightly the pressure normally maintained in that chamber. Accordingly I have provided the leak port 28a, the effectiveness of which may be controlled by the adjusting screw 28b.

Fig. 6 shows another construction differing somewhat from those above described in the details of construction, but operating in substantially the same manner. Its valve 23 when "closed" permits a minimum flow past it, as indicated by the arrows. Its valve stem 24 is connected to the piston 25 which divides the cylinder in which it is mounted into two chambers, viz., 26 which is open to the atmosphere and 27 which is open to the exhaust conduit beyond the valve 23.

The valve 23 is normally in the closed position illustrated. Upon the insertion of a carrier into the system the pressure in the exhaust conduit 20, and hence in the chamber 27, is decreased, with the result that the atmospheric pressure exerted in chamber 26 opens the valve 23 against the pressure of the spring 31.

The closing of this valve is accomplished as in the case of the structures described above, by means of a vane which is moved by the kinetic energy of the rush of air resulting from the exit of the carrier from the line. This vane 50 is normally held away from the port 51 by a spring 52. The distance it is retracted by the spring may be adjusted by means of the adjusting screw 53. Assume now that the valve 23 is open and a carrier is in transit. The vane 50 will be in the position shown in the drawing. Upon the exit of the carrier the rush of air pushes the vane 50 to the left so that it closes the port 51. This cuts off communication between the chamber 27 and the exhauster and leaves that chamber in free communication with the atmosphere through the bell mouth. In other words, the pressure on the two sides of the piston 25 is equalized sufficiently so that the spring 31 closes the valve 23, the vane 50 returning to the position illustrated.

In some of the appended claims I have employed the term "pneumatic" as a noun to designate any form of pressure actuated device, such, for example, as a diaphragm or piston. Obviously one of the illustrated forms of "pneumatic" may, without invention, be substituted for the other in any of the modifications illustrated.

The terms and expressions which I have employed are used as terms of description and not of limitation, and I have no intention, in the use of such terms and expressions, of excluding any mechanical equivalents of the features shown and described, or portions thereof, but recognize that various modifications are possible within the scope of the invention claimed.

What I claim is:

1. Pneumatic dispatch apparatus comprising a conduit and an exhauster connected therewith, a controlling valve located in the conduit, a minimum flow of air through the conduit being permitted when the valve is in closed position, a pneumatic exposed at one side to the pressure obtaining in the conduit and permanently exposed at the opposite side to atmospheric pressure; said pneumatic being adapted to open the air controlling valve when the pressure within the conduit is reduced due to the checking of said minimum flow by introducing a carrier into the conduit, and means responsive to increased flow of air through the conduit such as occurs when the carrier is discharged for equalizing the pressure upon opposite sides of the pneumatic to permit the valve to close.

2. Apparatus for use in a pneumatic dispatch system of the minimum flow, vacuum type having an air conduit, a normally closed main valve controlling the flow of carrier impelling air current through the conduit, a minimum flow of air through the conduit normally being permitted, a pneumatic sensi-

tively responsive to pressure change in the conduit, one side of the pneumatic being constantly exposed to full atmospheric pressure, mechanical means transmitting movement from the pneumatic to the valve to open the valve when the pressure in the conduit varies from normal due to introduction of a carrier into the conduit, and means sensitively responsive to increase in velocity of air in the conduit beyond a predetermined velocity for equalizing the pressure upon opposite sides of the pneumatic to permit the valve to close.

3. Apparatus for use in a pneumatic dispatch system of the minimum flow, vacuum type having an air conduit and an exhauster connected with the conduit, said apparatus comprising a valve for controlling the passage of carrier impelling air flow through the conduit, means normally holding the valve in closed position, a passage being provided to permit a minimum flow of air from one side of the closed valve to the other, a pneumatic constantly exposed at its outer side to atmospheric pressure and exposed at its inner side to the pressure obtaining in the conduit, an operating connection between the pneumatic and valve, the pneumatic operating to open the valve when pressure in the conduit drops below normal due to introduction of a carrier into the conduit, a normally closed valve adapted when opened to expose the inner side of said pneumatic to atmospheric pressure and a vane exposed to the air flowing through the conduit adapted to open said last named valve when the carrier is discharged from the conduit.

4. Power control apparatus for a pneumatic dispatch system of the vacuum minimum flow type having a conduit communicating with an exhauster, said apparatus comprising a valve normally closed to prevent a carrier propelling flow of air through the conduit, a minimum flow of air through the conduit being permitted, a pneumatic to actuate the valve for opening the latter when a carrier is introduced into the conduit, one side of the pneumatic being constantly exposed to full atmospheric pressure and the opposite side normally being exposed to pressure conditions obtaining within the conduit and means operating automatically upon delivery of a carrier from the conduit to admit full atmospheric pressure to act upon the latter side of the pneumatic.

5. Power control apparatus for a pneumatic dispatch system of the vacuum minimum flow type having a transmission tube and an exhauster connected to the tube, said apparatus comprising a valve for controlling air flow through the tube, a minimum flow of air through the tube being permitted when the valve is closed, a pneumatic constantly exposed upon its one side to atmospheric pressure and normally exposed upon its other side to the pressure obtaining in the trans-

mission tube, means connecting the valve to the pneumatic, and means operative upon the delivery of a carrier from the transmission tube to admit atmospheric pressure to act upon the inner side of the pneumatic.

6. Power control apparatus for use in a pneumatic dispatch system of the minimum flow type having a transmission tube communicating with an exhaust, said apparatus comprising a casing having a passageway connecting the transmission tube with the exhaust, a normally closed valve controlling said passageway, a minimum flow of air past the closed valve being permitted, a pneumatic connected to the valve for moving the latter, one face of the pneumatic being constantly exposed to the atmosphere and the other face of the pneumatic forming a movable wall for a chamber within the casing, the pressure in said chamber normally being below that of the atmosphere, and means exposed to the air flowing through the transmission tube and actuatable thereby to admit atmospheric pressure to said chamber.

7. Power control apparatus for a pneumatic dispatch system of the vacuum, minimum flow type having a transmission tube communicating with an exhaust, said apparatus comprising a hollow casing communicating with the transmission tube and provided with an apertured partition separating spaces in which the air pressure fluctuates, a valve controlling the passage of air through the aperture in said partition, an open passage being provided to permit a minimum flow of air from one of said spaces to the other, a pneumatic connected to the valve, the inner side of said pneumatic being exposed normally to the pressure obtaining in one of said spaces and the outer side being always exposed to full atmospheric pressure, and means responsive to sudden increase in velocity in air flow in the transmission tube and actuatable thereby to admit atmospheric pressure to act upon the inner side of the pneumatic.

8. Power control apparatus for a pneumatic dispatch system of the vacuum minimum flow type having a transmission tube, said apparatus comprising a casing connected to the transmission tube and having a passage connecting the transmission tube with an exhaust, a valve controlling the passage through the casing, a pneumatic connected to the valve, one face of the pneumatic being freely exposed to atmospheric pressure and the opposite face of the pneumatic forming a movable wall for a chamber within the casing, the pressure in said chamber normally being below that of the atmosphere, a port for admitting air at atmospheric pressure to said chamber, a vane exposed to the air flowing in the transmission tube and movable thereby, and an auxiliary valve actuatable by

the vane, said latter valve normally closing said air admission port.

9. Power control apparatus for a pneumatic dispatch system of the minimum flow type having a transmission tube, said apparatus comprising a casing, an apertured wall within the casing separating spaces in which air pressure fluctuates, a main valve controlling the flow of air through the aperture in said wall, a continuous minimum flow of air from one space to the other being provided for, the casing having an offset portion, a movable wall dividing said offset portion into two chambers, one of said chambers being freely open to the atmosphere and the other communicating with one of said spaces, an orifice for admitting air at atmospheric pressure to the last named chamber, an auxiliary valve normally closing said orifice, means automatically actuatable upon discharge of a carrier from the transmission tube to open said valve, and means for transmitting movements of the movable wall to the main valve.

10. Power control apparatus for a pneumatic dispatch system of the vacuum minimum flow type having a transmission tube communicating with an exhaust, said apparatus comprising a hollow casing provided with a main portion and an offset portion, an apertured partition dividing the interior of the main portion of the casing into two spaces, one of which communicates with the transmission tube and the other with the exhaust, a main valve normally closing the aperture in said wall, a continuous minimum flow of air from one space to the other being permitted, a movable wall dividing the offset portion of the casing into two chambers, one of said chambers communicating freely with the atmosphere and the other chamber communicating by a restricted passage with one of the spaces in the main part of the casing, the latter chamber having an orifice in its wall for admitting air at atmospheric pressure, an auxiliary valve normally closing said orifice, a movable baffle sensitively responsive to increase in velocity of air in the transmission tube incident to the delivery of a carrier from the latter, means connecting the baffle to the auxiliary valve, and means for transmitting movements of said movable wall to the main valve.

11. Power control apparatus for a pneumatic dispatch system of the vacuum minimum flow type having a transmission tube and a suction tube, said apparatus comprising a casing connected to the respective tubes and having a main portion and a secondary portion, an apertured wall dividing the interior of the main portion into two spaces communicating respectively with the transmission tube and the suction tube, a valve controlling the passage of air through the aperture in said wall, a movable wall divid-

ing the secondary portion of the casing into two chambers, a partition dividing one of said chambers from the space in the main casing which communicates with the transmission tube, a rod passing through an opening in the partition and connecting the main valve to said wall, and a channel providing for the passage of air from one side of the partition to the other.
